SIGNALING SYSTEM.

1,249,570.

Specification of Letters Patent. Patented Dec. 11, 1917.

Application filed December 29, 1916. Serial No. 139,553.

To all whom it may concern:

Be it known that I, STANLEY S. A. WATKINS, a subject of the King of Great Britain, residing at Mount Vernon, in the county of 5 Westchester and State of New York, have invented certain new and useful Improvements in Signaling Systems, of which the following is a full, clear, concise, and exact description.

10 This invention relates to signaling systems in which each signaling device is adapted for actuation by current of a single polarity, and is more particularly applicable to multi-station telephone lines wherein it is desirable to obtain selective signaling of the 15 several subscribers' stations.

In selective signaling system of this type, heretofore known, the margins of operation of the signaling devices have been comparatively low, or if these margins have been increased by the use of auxiliary apparatus in connection with the signaling devices, the margins obtainable in the associated supervisory signaling apparatus have been necessarily sacrificed. These defects have been caused by the lack of coöperation between the signaling devices and the source of signaling current, as will be hereinafter more fully explained.

30 One of the objects, therefore, of this invention is the provision of a source of signaling current to coöperate with the associated signaling devices in order to give satisfactory margins of operation, and, therefore, good selection. Another object of this invention is the production of a signaling system in which the signaling devices may be of such a nature that not only do they allow good selection in signaling, but at the 35 same time they do not impair the operation of the associated supervisory signaling apparatus. Still another object is the production of a source of signaling current of unitary structure, such as a generator, which 40 will coöperate with signaling devices in the manner previously mentioned.

The nature of the invention and the method of applying the same will be more clearly seen by reference to the accompanying drawings wherein:—

Figure 1 is a schematic representation of a telephone system embodying this invention; Fig. 2 is a diagrammatical representation of a source of current or a generator 55 suitable for use in the system of Fig. 1; Fig.

3 represents the wave form of the voltage generated by the generator; and Fig. 4 represents the wave form of the current flowing in the signaling devices during their actuation.

Referring now to Fig. 1, the telephone system there shown consists of a pair of line conductors 5, 6, with one end of which are associated subscribers telephone stations 7, 8, 9 and 10. The other end terminates in a 60 jack at a central station with which are associated the usual line relay 11, line lamp 12, and cut-off relay 13. A cord circuit 14 is adapted for connection with such line in the ordinary manner by means of a plug.

The usual telephonic apparatus located at each subscriber's station consists of a transmitter, receiver, condenser and induction coil, adapted to be connected in bridge of the line in a well-known manner, by the removal 70 of the receiver from the switchhook. In addition, at each station there is a signaling device 15 arranged to be connected permanently in series with the condenser 16 between one or the other of the line conductors 80 and ground. The signaling devices at stations 7 and 10 are connected between line conductor 5 and ground, while those at stations 8 and 9 are connected between the other line conductor 6 and ground. Each of these 85 signaling devices is operable by current of only a single polarity, and hence they may be what are commonly known as biased ringers. For the purpose of this description it will be assumed that the signaling devices or biased 90 ringers at stations 7 and 8 are adapted to operate on current of positive polarity only, while those at stations 9 and 10 will operate on current of negative polarity only. The 95 reason for using biased ringers and for connecting them into the circuit as just described is to obtain full selective ringing in a way hereinafter to be explained.

The cord circuit 14 is of the well-known common battery repeating coil type, having 100 a supervisory relay 17 and a four-button ringing key 18 adapted to connect signaling current of either positive or negative polarity to one or the other of the line wires depending upon which subscriber's station is 105 to be signaled.

The source of signaling current, symbolically shown in Fig. 1 as 19 and 20, may consist of a generator, such as diagrammatically shown in Fig. 2. This generator has 110

- four field poles 21, 22, 23 and 24, two of which are of one polarity and the other two of the opposite polarity, as shown by the symbols N, N and S, S. The two poles marked N, N are different in shape from those marked S, S. The ring armature 25 rotates within the field poles and is provided with four windings 26, 27, 28 and 29, each of which is concentrated on a small sector of the armature. The two windings on opposite sectors, such, for example, as 26 and 28, are connected in series, and in such a way as to aid each other. The terminals of one pair of windings are connected to slip rings 30, 31, and those of the other pair to slip rings 30, 32, in such a way that slip ring 30 is common to both pairs, while slip rings 31 and 32 are of opposite polarity at any instant of time.
- 20 The wave form of the alternating voltage generated by either pair of windings of such a machine is represented by Fig. 3, this particular wave shape being due to the flux distribution in the several poles. Since 25 the flux in the poles marked S, S is substantially equal to that in the larger poles marked N, N, it follows that the flux density is higher in the former, and, consequently, as the windings are passing under these poles 30 the maximum voltage generated will be higher than that of opposite polarity generated when the same windings are passing under the other pair of poles. It is also evident that the length of time occupied by 35 a set of windings in passing under the poles marked S, S will be less than that occupied while the same windings are passing under the poles marked N, N. These conditions are represented by the voltage wave of Fig. 3, 40 where voltage of one polarity is generated for a period of time represented by c and of maximum value a , while voltage of opposite polarity and of maximum value b , is generated for a length of time represented by d .
- 45 Such a voltage wave, when impressed upon the system of Fig. 1, produces a current in the signaling devices of substantially the wave form shown in Fig. 4; the form of the current wave being determined by the 50 relative values of the electrical constants of the system. As there shown a current of one polarity and of maximum value a' flows for a period of time represented by c' , while current of the opposite polarity, and of 55 maximum value b' , flows for the length of time represented by d' . While the amount of energy represented by either part of this current wave must necessarily be the same, the shape of the wave and the maximum 60 value of the current is quite different, and this difference in the maximum value of the current is substantially a measure of the margin of selection in the signaling devices, shown in Fig. 1.
- 65 The coöperation between the signaling de-

vices at the subscribers' stations and the source of signaling current will be more clearly seen from a description of the operation of the system, shown in Fig. 1.

Assume that the operator at the central 70 office wishes to signal a party at subscriber's station 7. The cord circuit 14 will be connected to the subscriber's line in the ordinary manner by means of the plug and jack, whereupon the cut-off relay 13 will operate 75 in a well-known manner to disconnect the line relay 11 from the line. The operator will then press the left-hand button of key 18, corresponding to station 7, which will impress signaling current from generator 80 19, whose maximum voltage is of positive polarity, upon the line. The path of this current will be from the grounded side of generator 19, left-hand upper alternate contact of key 18, line conductor 5, condensers 85 16 and signaling devices 15 of subscribers' stations 7 and 10 in parallel, to ground. Alternating current of wave form, shown in Fig. 3, will theréupon flow through the signaling devices 15, but only the device at subscriber's station 7, will be actuated, the signaling device at subscriber's station 10 not responding because the maximum value of the negative loop of the alternating current wave is not sufficiently high. In a similar 90 95 manner the signaling device at any of the other stations may be actuated by operating the button of ringing key 18 at the central office corresponding to that station.

A wave form, substantially as shown in 100 Fig. 3, has been found to give the most satisfactory results, and such a wave form can be obtained by the use of the generator hereinbefore described, coöperating with a condenser 16 and a biased ringer 15. In the 105 systems and with the sources of current heretofore available, it has been necessary to use a non-inductive resistance in shunt with the condenser in order to obtain approximately this same wave form of current. In those 110 systems, however, the trouble, before noted, of decreased marginal operation of the supervisory relays, was experienced. The introduction of such resistance furnished a leakage path for battery, from the ring side 115 of the line to ground, which path included the supervisory relay 17. Such leakage path may be traced from the central office battery through one winding of the repeating coil, supervisory relay 17, normal contacts of the 120 ringing key 18, ring contacts of the plug and jack, line wire 6, non-inductive resistance (not shown), in shunt about the condenser and the biased ringers 15 of stations 8 and 10 in parallel to ground. Thus, a current 125 will flow continuously through supervisory relay 17 as long as the cord circuit and line are connected for conversation, through the plug and jack, and, therefore, will cut down the margin of operation of the relay 17. 130

This defect is clearly eliminated in the system provided by this invention because there is no opportunity for such a leak to occur.

In any of the other systems in which such 5 non-inductive resistance has not been used, it has not been possible to obtain a wave form such as shown in Fig. 3, and therefore, the margin of selection in the signaling devices has been comparatively low, and those 10 systems have consequently been impractical.

In the foregoing description the source of signaling current or the generator has been represented as a four-pole machine having four windings, each concentrated 15 upon a comparatively small sector of the armature. It is, of course, evident that two poles or any multiple thereof, could be used instead, providing the location of the windings were changed correspondingly.

20 Another variation within the scope of this invention is to increase the number of windings on the armature to completely utilize the available winding space, in which case each set of windings could be terminated on 25 a pair of slip rings individual thereto or the sets could be terminated in pairs on three slip rings as shown in Fig. 2. By this arrangement a more efficient and compact machine would result.

30 It is further to be understood that other types of armatures and armature windings may be used in connection with this type of field structure to produce substantially the same results as hereinbefore described, and 35 their use will accordingly come within the scope of this invention, as defined by the accompanying claims.

What is claimed is:

1. In a selective signaling system, line 40 conductors, a plurality of biased signaling devices connected thereto, a signaling current generator comprising a plurality of magnetic poles of opposite polarities, a pole of one polarity being of different shape 45 than a pole of the opposite polarity, and switching means for connecting said generator to one of said line conductors.

2. In a selective signaling system, line 50 conductors, a plurality of biased signaling devices connected thereto, a signaling current generator comprising a plurality of magnetic poles of opposite polarities, a pole of one polarity being of different shape than a pole of the opposite polarity, an armature 55 for said generator having a concentrated winding, and switching means for connecting said generator to one of said conductors.

3. In a selective signaling system, line 60 conductors, a plurality of biased signaling devices connected thereto, a condenser in series with each signaling device, a signaling current generator comprising a plurality of magnetic poles of opposite polarities, a pole of one polarity being of different shape 65 than a pole of the opposite polarity, and

switching means for connecting said generator to one of said line conductors.

4. In a selective signaling system, line 70 conductors, a plurality of biased signaling devices connected thereto, a condenser in series with each signaling device, a signaling current generator, an armature therefor having a concentrated winding, and switching means for connecting said generator to one of said conductors. 75

5. In a selective signaling system, line 80 conductors, a plurality of biased signaling devices connected thereto, a condenser in series with each signaling device, a signaling current generator comprising a plurality of magnetic poles of opposite polarities, a pole of one polarity being of different shape than a pole of the opposite polarity, an armature for said generator having a concentrated winding, and switching means 85 for connecting said generator to one of said conductors.

6. In a selective signaling system, a line 90 conductor, a plurality of biased signaling devices connected thereto, a signaling current generator comprising a plurality of magnetic poles of opposite polarities, a pole of one polarity being of different shape than a pole of the opposite polarity, an armature therefor having two similar concentrated 95 windings oppositely wound with respect to the magnetic field between said poles, and switching means for connecting either of said windings to said line conductor.

7. In a selective signaling system, a line 100 conductor, a plurality of biased signaling devices connected thereto, a condenser in series with each signaling device, a signaling current generator comprising a plurality of magnetic poles of opposite polarities, a pole of one polarity being of different shape than a pole of the opposite polarity, an armature therefor having two similar concentrated 105 windings oppositely wound with respect to the magnetic field between said poles, and switching means for connecting either of said windings to said line conductor. 110

8. In a selective signaling system, a two-conductor telephone line terminating at a 115 central office, a plurality of subscribers' stations connected thereto, a biased signaling device individual to each subscriber's station, two of said signaling devices being connected to each of said conductors and the two signaling devices which are connected to the same conductor being oppositely biased, a signaling current generator comprising a plurality of magnetic poles of opposite polarities, a pole of one polarity being of different shape than a pole of the opposite polarity, an armature therefor having two similar concentrated windings 120 oppositely wound with respect to the magnetic field between said poles, and switching means 125 130

for connecting either of said windings to either of said line conductors.

9. In a selective signaling system, a two-conductor telephone line terminating at a central office, a plurality of subscribers' stations connected thereto, a biased signaling device individual to each subscriber's station, two of said signaling devices being connected to each of said conductors, the 10 two signaling devices which are connected to the same conductor being oppositely biased, a condenser in series with each signaling device, a signaling current generator

comprising a plurality of magnetic poles of opposite polarities, a pole of one polarity 15 being of different shape than a pole of the opposite polarity, an armature therefor having two similar concentrated windings oppositely wound with respect to the magnetic field between said poles, and switching 20 means for connecting either of said windings to either of said line conductors.

In witness whereof, I hereunto subscribe my name this 28th day of December A. D., 1916.

STANLEY S. A. WATKINS.
